DESIGN FOR A CONVERTIBLE TRUNK OR SIMILAR ARTICLE

William J. Begg, New York, N. Y.

Application June 14, 1937, Serial No. 69,833

Term of patent 14 years

To all whom it may concern:

Be it known that William J. Begg, citizen of the United States of America and resident of New York, in the city of New York and State of New York, has invented a new, original, and ornamental Design for a Convertible Trunk or Similar Article, of which the following is a specification, reference being had to the accompanying drawings forming part thereof, in which,

Fig. 1 is a rear perspective view of a trunk embodying my design, illustrating the closed position thereof;

Fig. 2 is a top plan view of the trunk shown in Fig. 1 but illustrating the same in partly opened position;

Fig. 3 is a front perspective view thereof illustrating the same in fully opened position with the panels A and B slidably removed, and the hinged base C in downwardly swung position from its normal position at right angles thereto;

Fig. 4 is a front perspective view similar to Fig. 3, with the door swung to open position showing the interior, and with one of the panels, A and B of Fig. 1 in place and the other slightly withdrawn; and

Fig. 5 is a front perspective view similar to Fig. 3, but with the panels A and B in place and with one of the base panels C in closed position and the other in slightly open position.

I claim:

The ornamental design for a convertible trunk or similar article, substantially as shown and described.

WILLIAM J. BEGG.
